UNITED STATES PATENT OFFICE.

WILLIAM H. PERRY, OF CONCORD, NEW HAMPSHIRE.

DESIGN FOR A MONUMENT.

SPECIFICATION forming part of Design No. 23,457, dated July 10, 1894.

Application filed June 13, 1894. Serial No. 514,478. Term of patent 7 years.

To all whom it may concern:

Be it known that I, WILLIAM H. PERRY, a citizen of the United States, residing at Concord, in the county of Merrimac and State of New Hampshire, have invented and produced a new and original Design for a Monument, of which the following is a specification, reference being had to the accompanying drawing.

This design relates more particularly to the configuration of the shaft, and the several forms of ornamentation of said shaft, the pedestal, and the base, also the character of finish for the different parts which will be fully set forth in the following specification and claim and clearly illustrated in the accompanying drawing, to which reference will be made by means of figures and letters.

The base 1, is oblong, and has four vertical sides which terminate in an obtuse frustum of a pyramid 2. The pedestal 3, has also an oblong form and four vertical sides terminating in an acute frustum of a pyramid 4, one or more sides of which may have a raised tablet 5, as shown.

The oblong shaft has four vertical sides 6, ornamented at bottom and top by the raised tablets respectively 7,—8, their upper and lower edges respectively being beveled as at 9—10. The shaft is further ornamented with the tablets 11 and 12, on one or both its longer sides, and with the tablets 13, on its shorter

sides or ends, all of which are of the configuration shown by a heavy border line, and further distinguishable by a finish of a different character.

The various styles of finish are also a feature of my design, and are designated by letters of reference—A, representing rock work, B, hammered work, and C, polished work.

The upper edge of the tablet 8, is curvilinear as shown at 14, and leaves the depressed surfaces 15, terminating at their top in the frustum of a pyramid 16, upon the top of which is a flat block, square or nearly square at its top, and somewhat wider than said frustum 16, so that two of its sides 17, and portions of its ends 18, project downward upon the longer sides of said frustum 16. The central portion of each edge of said block is beveled off, as at 19, and all corners of said block are finished with a "draft line" 20.

Having described my new design, what I claim is—

The design for a monument substantially as herein shown and described.

In testimony whereof I affix my signature in presence of two witnesses.

WILLIAM H. PERRY.
